Inventor,
Abijah S. Parker
by Stein & Rock his Atty.

UNITED STATES PATENT OFFICE.

ABIJAH S. PARKER, OF CINCINNATI, OHIO.

HUB-BAND.

SPECIFICATION forming part of Letters Patent No. 274,136, dated March 20, 1883.

Application filed October 12, 1882. (No model.)

To all whom it may concern:

Be it known that I, ABIJAH S. PARKER, a citizen of the United States, residing at Cincinnati, county of Hamilton, and State of Ohio, have invented certain new and useful Improvements in Bands for Vehicle-Hubs, of which the following specification is a full, clear, and exact description, reference being had to the accompanying drawings, making part of this specification.

My improvements relate more particularly to that class of hub-bands which are secured upon the outer ends of the hubs, and are provided with ornamental linings, usually of brass, and either nickel, gold, or silver plated. Heretofore these linings have been secured to the bands by solder, applied either at their outer or inner edges, or both—a means of attachment requiring much labor, and which, owing to the heat required, frequently destroyed or marred the finish of the plated lining.

The object of my invention is to provide means for attaching the lining without the use of solder by self-locking the lining to the band.

The novelty consists in the combination, with a hub-band, of an ornamental lining secured in its outer end by a self-lock, without the use of solder or other means, as will be herewith set forth and specifically claimed.

In the accompanying drawings, Figure 1 is a central sectional view taken diametrically through my improved hub-band with lining applied. Fig. 2 is a corresponding view of the ornamental lining and of the band with lining attached. Figs. 3 and 4 are corresponding views, showing a modification in the construction of the band for the purpose of attaching the lining.

The same letters indicate like parts in all the figures.

A is the hub-band, of cast metal, which may or may not be malleable. At or about its center is an internal integral annular flange, B, having a twofold purpose—namely, to strengthen the band against splitting when being driven onto the hub, and to serve as a retaining-shoulder for the lower or inner edge of the ornamental lining C. This lining is of brass, usually spun to the shape shown in Fig. 2, and of such size as to snugly fit into the outer end of the band A, and with its inner end passing snugly through the flange-opening. Before it is applied to the band it is plated with gold, silver, or nickel, as desired, and is then slipped into the band, as before stated. Now, by means of dies of suitable shape, or by spinning, its edges are upset, the inner against the under side or shoulder, a, of the flange B, and the outer upon the outer edge of the band, as shown clearly in Fig. 3. By this means the lining is securely self-locked, and can be secured to the band without injury to its plated surface.

Instead of the flange B as a means for securing the inner upset end of the lining, the construction shown in Figs. 3 and 4 may be employed. In this instance a circumferential groove, c, is cast or cut in the band near its middle, on the inside, and into this groove the inner edge of the lining is upset to form the lock.

Having thus fully described my invention, I claim—

In combination with a hub-band, an ornamental lining secured therein by having its edges upset, whereby it becomes self-locked and is securely held in proper position.

A. S. PARKER.
